(57) **CLAIM**

The ornamental design for a flatware handle, as shown and
described.

DESCRIPTION

FIG. 1 is a top view of my invention on a fork;
FIG. 2 is a side elevational view of the fork illustrated in
FIG. 1;

FIG. 3 is a bottom view of my invention on a fork;
FIG. 4 is a side elevational view of the opposite side of my
invention illustrated in FIG. 2;

FIG. 5 is a cross sectional view taken along lines 5—5 of
FIG. 1;

FIG. 6 is a side elevational view of a second embodiment of
my invention on a knife;

FIG. 7 is a top view of the knife illustrated in FIG. 6;
FIG. 8 is the opposite side elevational view of my invention
on a knife;

FIG. 9 is a bottom view of my invention on a knife;
FIG. 10 is a cross sectional view taken along lines 10—10
of FIG. 6;

FIG. 11 is a top view of my invention on a spoon;
FIG. 12 is a side elevational view of the spoon illustrated in
FIG. 11;

FIG. 13 is a bottom view of my invention on a spoon;
FIG. 14 is a side elevational view of the opposite side of my
invention illustrated in FIG. 12; and,

FIG. 15 is a cross sectional view taken along lines 15—15
of FIG. 11.

The front and rear views of the knife, fork and spoon would
not show my flatware handle design.

The broken line showing of a portion of the knife, fork and
spoon is for illustrative purposes only, and forms no part of
the claimed design.
